(57) **CLAIM**

The ornamental design for an orthopedic ramp shape foot supporting pad, as shown and described.

DESCRIPTION

FIG. 1 is a top view of an orthopedic ramp shape foot supporting pad, showing my new design;

FIG. 2 is a bottom view thereof, shown in an environment of use;

FIG. 3 is a left side view thereof;

FIG. 4 is a bottom view thereof, shown in another environment of use;

FIG. 5 is a bottom view thereof, shown in a left and right environments that mirror each other;

FIG. 6 is a bottom view thereof, shown in another environment; and,

FIG. 7 is a bottom view thereof, shown in another environment.

The broken lines showing of a foot or insole in FIG. 2, FIG. 4, FIG. 5, FIG. 6, and FIG. 7 illustrate environment structure and form no part of the claimed design.

1 Claim, 2 Drawing Sheets
